EXTRUSION APPARATUS

William Klocke, Woodhaven, N. Y., assignor to
 E. W. Bliss Company, Brooklyn, N. Y., a corpora-
 tion of Delaware

Application October 23, 1943, Serial No. 507,417

1 Claim. (Cl. 207—2)

1

This invention relates to improvements in extrusion apparatus and, more particularly, to apparatus in which a sleeve functions as a sliding die which confines a hot billet laterally and slides telescopically relatively to a forming die as the billet substance is moved with the sleeve and pressed through the said forming die to give it a desired form, such as, for example, that of a rod, tube, rail, strip, or the like.

My United States Patent No. 2,167,845, granted August 1, 1939, discloses telescopically co-acting sleeve and forming dies of the general character just mentioned and an extrusion method in which the present invention may be employed; also mechanical die actuating means, including an air cylinder for actuating a sleeve die and a crank mechanism for actuating a cap for pressing billet metal toward and through a forming die, the said pressing cap, at the same time, serving to move the sleeve die, whereby to confine the billet metal against spreading laterally. The several die actuating means disclosed in said patent, or other suitable means, may be employed in practising the present invention and, hence, are not disclosed herein.

In forming metal and other substances into desired shapes, it is necessary to heat the substance to give it sufficient plasticity to enable it to be extruded through a forming die. A substantial measure of the heat, of course, passes into the sleeve die and the forming die, and, as the two said dies may be of different dimensions or composition, they may not expand uniformly; therefore, unless the two said dies are given a relatively loose telescopic fit, the unequal expansion may cause the two to bind and cause operational difficulties or damage. This situation may be aggravated by additional heat generated by the friction of the metal passing over the die surfaces and further aggravated by the lateral force exerted upon said dies by the billet substance during its extrusion.

The provision of a loose telescopic fit between the sleeve and forming dies makes it necessary to provide simple and effective means for preventing the substance being extruded from entering the clearance between the two dies, as, under the latter conditions, such substance itself would cause binding of the dies.

The principal object of the present invention is the provision of effective sealing means for sealing the clearance between the sleeve and forming dies, whereby to prevent ingress of billet metal or other substance into said clearance.

A further object is the provision of such seal-

2

ing means which may conform to sealing surfaces upon each of the two said dies in response to a physical condition, such as heat or pressure which may be generated in the substance being extruded.

These and other objects are accomplished, in general, according to the present invention, by the provision of an expansible sealing member, which may be in the form of a gasket or ring, 10 having a first sealing surface adapted to engage a sealing surface at the input end of the forming die, a second sealing surface adapted to engage the interior surface of the sleeve die, and a third surface, which, advantageously, may be a diagonal surface, adapted to receive an outwardly directed force from the extrusion substance, for expanding the sealing member so that its mentioned sealing surfaces effect and maintain an effective sealing engagement with both the said 20 dies to prevent extrusion substance from entering the space between the two said dies.

For illustrative purposes only, and without limiting the invention thereto, the invention is shown in the accompanying drawings—in which

25 Figs. 1, 2, and 3 are somewhat diagrammatic, substantially central, vertical sectional views of the invention as employed to extrude metal with several dies, showing, respectively, the positions of the dies and the billet metal in first, intermediate, and final parts of a pressing portion of an extrusion cycle;

Fig. 4 is a top plan view of a preferred form of sealing ring;

Fig. 5 is a cross-sectional view of said ring, on 35 the line 5—5 of Fig. 4;

Fig. 6 is an enlarged detail of a portion of the structure as illustrated in Fig. 3, and

Fig. 7 is a view, somewhat similar to Fig. 5, of a modified form of sealing ring.

40 Inasmuch as the functioning of the sealing means, yielding the desired results, occurs during the pressing portion of an extrusion cycle, Figs. 1, 2, and 3 should afford a clear general understanding of the invention. In these figures are shown a cylindrical female forming die 11, fixed in upright position upon a bolster or bed 12, directly over an opening 12a provided in the latter to permit an extruded form to pass downwardly from said die through the said bed. The die 11 is provided with an input opening 11a defined by an inwardly enlarged, annular, forming lip 11b.

45 A cylindrical sleeve die 13 is adapted to be reciprocated vertically in loose telescopic relationship to the forming die 11, by rods 14 which are

fixed to the lower end of said sleeve die and extend downwardly therefrom through suitable openings in the bed 12. The rods 14 may be connected to suitable actuating means (not shown), as, for example, an air actuated piston, as disclosed in my said patent, adapted to move the said rods and the sleeve die upwardly to bring the upper end of the latter into engagement with the under-side of a pressing cap 15 which, with the sleeve die 13, defines a chamber 16, adapted to receive a suitably heated billet A of metal to be extruded.

The pressing cap 15 may be reciprocated vertically by suitable means (not shown) acting through a slide 17 to the under-side of which the cap 15 is fixed. In apparatus, as illustrated in the accompanying drawings, adapted to extrude metal into tubular form, the slide 17 may be provided with a chamber 18 within which a plunger 19 is suitably adapted to reciprocate and actuate a punch 20, which is fixed to the under-side of the plunger 19 and extends through the pressing cap 15 and is adapted, when moved downwardly, to pass through the billet metal into a central position within the forming lip of the forming die 11, where it functions as an internal die in imparting a tubular form to the extruded metal.

The loose relationship between the forming die 11 and the sleeve 13 is not apparent from Figs. 1, 2, and 3; but, in Fig. 6, it may be seen that the said dies are so proportioned as to afford a clearance 21 therebetween to allow for unequal expansion of the two said dies. In order to seal said clearance against the ingress of billet metal thereinto, an expandible sealing member 22, preferably in the form of a metal ring of triangular cross-section, is disposed upon the upper end of the forming die 11 and is adapted to expand into sealing and sliding engagement with the sleeve die 13.

As best seen in Figs. 5 and 6 the sealing ring 22, preferably, has a radial sealing surface 22^a, normal to a circumferential sealing surface 22^b of said ring, which surfaces respectively, are adapted to effect a sealing engagement with an upper end surface 11^c of the forming die 11, and a sealing and sliding engagement with the inside surface of the sleeve die 13. The sealing surface 22^b, preferably, is of a substantial width, as shown in the drawings, to assure that the ring will slide smoothly upon the inside surface of the sleeve die 13 without scoring the latter surface. Also, by providing that the angle between the surfaces 22^a and 22^b of the sealing ring be identical with the angle between the inside surface of the sleeve die 13 and the surface 11^c of the forming die 11, the sealing ring 22, under the pressure encountered in an extrusion operation, is forced and held firmly within the angle between the two last-mentioned surfaces. Thus, the surface 22^b is prevented from assuming any angularity with respect to the inside surface of the sleeve die. Because of this, the possibility of the latter surface becoming scored is obviated. The ring 22, preferably, is also provided with a diagonal surface 22^c which faces inwardly and upwardly and serves two chief purposes, to guide the billet metal inwardly to the input opening 11^a of the forming die 11, and to receive an outwardly directed force from the billet metal to expand the ring 22 into a firm sealing and sliding engagement with the inner wall of the sleeve die 13 and to hold the said ring down firmly into sealing engagement with the top of the forming die 11.

The ring 22 may be rendered expandible by splitting it, as by a straight cut 22^d (Figs. 4 and 5), which preferably passes diagonally through a section of the ring. The diagonal extension of the cut 22^d, as best seen in Fig. 5, may be considered as being helical with regard to the ring's axis. A diagonal cut, as just described and illustrated, not only permits expansion of the ring, but functions to trap billet metal to prevent its passage through the ring into the clearance 21.

The split in the sealing ring, instead of being effected by a straight cut, as just described, may have portions 22^e, 22^f, and 22^g (Fig. 7) which are angular to each other and which may function to trap and prevent passage of billet metal through the split. In such a ring structure, the pressure of billet metal, passing through the ring, may operate to press the split closed at the cut portion 22^f, or the angular split may function as a labyrinth, effectually preventing passage of billet metal through the split.

Although the ring structures illustrated and described are preferred, the split may be effected, within the invention, by any type of cut which will render the sealing ring expandible, and prevent material passage of billet metal through the split. Also, within the invention, the sealing ring, instead of being split to render it expandible, may be composed of material which, when subjected to the heat or pressure of the billet metal, may become extended sufficiently to yield the necessary expansion of the ring. The composition of the ring, also, may be so chosen as to yield a particular function; thus, it may be of a metal adapted to lubricate the billet metal as it is constricted in its passage toward the forming die, or of a metal which may resist the heat encountered, whereby to assure its proper functioning for the duration of an extrusion cycle. The ring, ordinarily, is intended to be used only in a single extrusion cycle.

At the beginning of an extrusion cycle, the sleeve die 13 is in its lowermost position about the forming die 11, as shown in Fig. 3, and the pressing cap 15 and the punch 20 are somewhat above their positions as shown in Fig. 1, thus leaving a clearance space above the forming die 11.

The first step in the cycle is the placing of the ring 22 in position upon the top of the forming die 11, with the surface 22^c facing inwardly and upwardly, as shown in Fig. 6. Then the hot metal billet A is placed upon said ring, the sleeve die 13 is moved upwardly to surround the billet, and the pressing cap 15 is moved downwardly into engagement with the upper end of the sleeve die. Then, with the parts in the positions substantially as shown in Fig. 1, the punch 20 is forced downwardly through the billet metal to its lowermost position relatively to the pressing cap 15, bringing the lower end of the said punch to a position within the input opening 11^a of the forming die 11, substantially as shown in Fig. 2, in which the billet metal displaced by the punch 20 has been extruded into tubular form, as at AA. Thereafter the punch 20 and the pressing cap 15 are forced downwardly together, to positions substantially as shown in Fig. 3, pressing most of the billet metal through the forming die 11 into complete tubular form, as at AAA; the sleeve 13, meanwhile, being forced downwardly by the cap 15 and serving to confine the billet metal against lateral deformation.

It will be understood that, during the downward flow of the billet metal, the latter is under pressure which exerts a force upon the diagonal

surface 22^c of the ring 22 substantially in the directions indicated by arrows in Figs. 1 and 6, thus operating to expand the said ring outwardly into a firm sealing and sliding engagement with the inner wall of the sleeve die 13, and to press the said ring downwardly and hold it down into firm sealing engagement with the top surface 11^c of the forming die 11. Thus the ring 22 serves as a very effective means for sealing the clearance 21 against the entry of billet metal thereinto and permits use of the disclosed telescoping die arrangement with its attendant advantages.

After completion of the extrusion of a billet of metal, as hereinbefore described, the several dies may be moved to open positions and the ring 22, together with the adjacent unextruded flash metal remaining above the forming die 11, may be cut off in any suitable manner. A new sealing ring may then be inserted in position, as already described, as a preliminary step in a succeeding extrusion cycle.

The present invention, although described and illustrated with reference to the extruding of metal into a tubular form, may be employed in extruding other materials and for producing rods, as disclosed in my mentioned patent, or producing other forms by extrusion.

Inasmuch as the invention may be practiced in ways other than those illustrated and described or mentioned herein, it is not to be considered as limited except as defined in the following claim.

What I claim is:

In extrusion apparatus, the combination of a die member having an axially extending extrusion aperture and a substantially radially-extending surface at the input end of said aperture; a sleeve member substantially surrounding said die member and being telescopically reciprocable relatively thereto and partially defining a variable-volume billet chamber, the said sleeve member having a cylindrical inner surface and sufficient clearance between the latter surface and an adjacent outer surface of the said die member to permit expansion and contraction of said members which may modify said clearance without material resultant binding of said members; and

means for diverting billet material in said billet chamber from said clearance and for guiding such material toward said extrusion aperture, the said means comprising an expansible sealing ring which is substantially non-deformable in radial cross-section, and has an outer cylindrical first sealing surface of substantial width in substantially intimate face to face relation with said cylindrical inner surface of the sleeve member, a second sealing surface extending radially inwardly substantially from one side of said first sealing surface, across said clearance, and into substantially intimate face to face and parallel relation with respect to the mentioned radially-extending surface of said die member, and a billet-engaging surface within and extending at least partially across the angle formed by the mentioned first and second sealing surfaces, the said billet-engaging surface being substantially open to the interior of said billet chamber whereby to receive pressure directly from a billet in said chamber to forcibly expand said ring into sealing engagement with said cylindrical inner surface of the sleeve member and to urge said ring into sealing engagement with said radially-extending surface of said die member whereby to divert billet material from said clearance and guide it toward said aperture.

WILLIAM KLOCKE.
